US00D882068S

(12) **United States Design Patent** (10) **Patent No.:** **US D882,068 S**
(45) **Date of Patent:** **** Apr. 21, 2020**

(54) **GAS EXCHANGE MEDICAL APPARATUS**

(71) Applicant: **Xenios AG**, Heilbronn (DE)

(72) Inventor: **Georg Mattheis**, Heilbronn (DE)

(73) Assignee: **Xenios AG**, Heilbronn (DE)

(**) Term: **15 Years**

(21) Appl. No.: **29/667,061**

(22) Filed: **Oct. 18, 2018**

Related U.S. Application Data

(63) Continuation of application No. 35/501,962, filed on Oct. 14, 2016 (U.S. filing date under 35 U.S.C. 384), and having an international filing date of Oct. 14, 2016, now abandoned.

(57) **CLAIM**

The ornamental design for a gas exchange medical apparatus, as shown and described.

DESCRIPTION

FIG. 1 is a front view of the gas exchange medical apparatus, showing my new design;

FIG. 2 is a top plan view thereof;

FIG. 3 is a bottom plan view thereof;

FIG. 4 is a left side view thereof;

FIG. 5 is a right side view thereof; and,

FIG. 6 is a perspective view thereof.

In the drawings, the broken lines are for the purpose of illustrating environment only and form no part of the claimed design.

1 Claim, 5 Drawing Sheets
